DESIGN FOR A RING MOUNTING

Frank Milhening, Evanston, Ill., assignor to J. Milhening, Inc., Chicago, Ill., a corporation of Illinois

Application August 31, 1938, Serial No. 79,655

Term of patent 7 years

To all whom it may concern:

Be it known that I, Frank Milhening, a citizen of the United States, residing at Evanston, in the county of Cook and State of Illinois, have invented a new, original, and ornamental Design for a Ring Mounting, of which the following is a specification, reference being had to the accompanying drawing forming a part thereof.

In the drawing:

I claim:

The ornamental design for a ring mounting, substantially as shown.

FRANK MILHENING.
